SHOE-SUPPORTING MEANS FOR SHOE MACHINES

Bernhardt Jorgensen, Marblehead, Mass., assignor to United Shoe Machinery Corporation, Flemington, N. J., a corporation of New Jersey

Original application February 4, 1941, Serial No. 377,347. Divided and this application March 24, 1942, Serial No. 435,990

10 Claims. (Cl. 12—123)

This invention relates to shoe-supporting means for shoe machines, this application being a division of a copending application of mine for Letters Patent for improvements in Machines for use in the manufacture of shoes, Serial No. 377,347, filed on February 4, 1941. While the invention is herein illustrated as applied to a machine of the character shown in that application, which is a machine for lasting shoes, it will be understood that it is not limited to machines of that particular kind.

For supporting a shoe and its last, herein frequently referred to inclusively as the shoe, against pressure applied on the bottom of the shoe, the invention, in one aspect, provides a toe rest and an instep support and novel means for controlling them in such manner as to permit them to adjust themselves to the shoe by relative movement heightwise of the shoe. As herein illustrated, the toe rest and the instep support are controlled by fluid-operated means comprising cylinders and pistons therein for moving them respectively into their shoe-supporting positions while permitting them thus to adjust themselves to the shoe, the cylinders being in communication with each other and the admission of the fluid thereto being controlled by a valve common to both of them. Preferably, as shown, the cylinder and piston associated with the toe rest are of greater diameter than the cylinder and piston associated with the instep support, so that adequate pressure is applied by the toe rest to clamp the shoe against a member engaging the bottom of its forepart while any danger of tipping the shoe by the pressure of the instep support thereon is avoided. Preferably the operating fluid is a liquid, such as light oil, and to cause the toe rest and the instep support to control the shoe in a substantially positive manner after their engagement with it, the invention provides for locking the fluid in the operating means.

The invention further provides novel means for supporting the shoe by engagement with its heel-end face. For this purpose, the construction shown comprises a heel rest having members arranged to press on the heel-end face of the shoe respectively in different locations heightwise of the shoe, these members being movable relatively to each other about different axes extending laterally of the shoe and movable also as a unit about another such axis to permit them to adjust themselves to the shoe. As illustrated also the heel rest, similarly to the toe rest and the instep support, is moved into operative position by fluid-operated means and is maintained in a

substantially positive manner in that position by control of the operating fluid.

The above and other features of the invention, including various novel details of construction and combinations of parts, will now be more particularly described with reference to the accompanying drawings and thereafter pointed out in the claims.

In the drawings,

10 Fig. 1 is a view partly in left-hand side elevation and partly in section of a portion of the machine shown in the above-mentioned application, showing shoe-supporting means provided by the present invention in operative relation to a shoe;

15 Fig. 2 shows partly in elevation and partly in section mechanism with which the machine is provided for controlling the flow of operating fluid to and from the means for operating the toe rest and the instep support;

20 Fig. 3 is a vertical section lengthwise of the shoe through the heel rest and a portion of its supporting means with the parts in their inoperative positions;

25 Fig. 4 is a section on the line IV—IV of Fig. 3; and

30 Fig. 5 is a partly diagrammatic and partly sectional view illustrating more fully than Fig. 1 the character of the means for operating the heel rest and showing a valve which controls the flow of fluid to and from this operating means.

35 The machine shown in the previously mentioned application is a lasting machine having various lasting instrumentalities which cooperate to last the toe end of a shoe positioned bottom upward, some of which instrumentalities are shown in Fig. 1 but need not be particularly described for an understanding of the present invention. They include wipers 2 for wiping the 40 marginal portion of the upper inwardly over an insole on the last and for pressing it down on the insole. The shoe is positioned in proper relation to these instrumentalities by a member 3 which engages the bottom of the toe end of the 45 insole and by a plurality of pins 4 which extend through holes in the insole into holes provided in the last. The operator mounts the shoe on the pins 4 with the insole in engagement with the member 3 prior to the starting of the power 50 operation of the machine. After the starting of the machine a toe rest 6 and an instep support 8 are moved upwardly to clamp the shoe against the member 3 and to support it thereafter against any downward movement in response, for example, to pressure of the wipers 2 thereon, and

a heel rest 10 is moved lengthwise of the shoe into engagement with its heel-end face to assist in supporting it against displacement in a heelward direction in the lasting operation. The toe rest comprises a rubber pad 12 arranged to engage the top of the toe end of the upper and a metal holder 14 for the pad, this holder having a lower end portion formed to fit in a cylinder 16 which is part of a casting 18 secured at its lower end to a frame casting 20. A depending portion 22 of the holder 14 extends into a bore in a piston 24 movable in the cylinder 16 and is connected rigidly to the piston by a cross pin 26 which extends into slots 28 formed in opposite sides of the cylinder. The toe rest 6 and the piston 24 are thus movable as a unit between limits determined by the pin 26 and the slots 28, the means for thus limiting upward movement of the parts being effective in case there is no shoe in the machine. Upward movement of the toe rest into clamping position results from the admission of fluid, preferably light oil, to the cylinder 16 through a pipe line 30 which leads from a chamber 32 (Fig. 2) to which fluid is supplied under pressure from a reservoir 33 (Fig. 5) as fully disclosed in the previously mentioned application. Such movement of the toe rest is effected against the resistance of a pair of springs 34, one of which is shown in Fig. 1, connected to the ends of the pin 26 and to the base of the cylinder 16. It will be understood that these springs serve, when permitted, to return the toe rest to its initial position.

The instep support 8 also is operated by fluid from the pipe line 30. It comprises a block 36 which engages the instep portion of the upper or the last, the block being preferably made of wood to provide a positive support without danger of injuring the upper by contact therewith and being mounted on the upper end of a rod 38 which serves as a piston vertically movable in a cylinder 40 formed as part of the casting 18 and communicating at its lower end through a passage 42 with the cylinder 16. The block 36 has a concave face 44 which substantially fits a convex face on the holder 14 to prevent the block from turning. A pin 46 extends from the holder 14 into a slot 48 in the block 36 to serve by engagement with a plate 50 pinned to the piston 38 to prevent any accidental movement of the piston entirely out of the cylinder 40. The piston 38 is of much smaller diameter than the piston 24, and accordingly the instep support is forced against the shoe or last with less pressure than the toe rest to avoid any tipping of the shoe by the action of the instep support thereon. The instep support, when permitted, is returned to its initial position by a pair of springs 52 at opposite sides of the cylinder 40. The plate 50 serves by engagement with the upper end of the cylinder to limit the downward movement of the instep support.

The above-mentioned chamber 32 is formed in a casting 54 shown fragmentarily in Fig. 2, this casting being fast on a plate 56 which serves as a closure for the chamber. The admission of fluid to the cylinders 16 and 40 for operating the toe rest and the instep support and the exhaust of fluid from the cylinders are controlled by a sleeve valve 58 which is slidably movable on a tube 60 clamped tightly between the casting 54 and a coupling 62 communicating with the pipe line 30. The tube 60 has therein a partition 64 which closes communication between its opposite ends, and extending through the tube at opposite

sides of this partition respectively are two sets of ports 66 and 68. The valve 58 is provided with an annular chamber 70 through which the ports 66 and 68 are in communication with each other when the valve is in position to admit fluid from the chamber 32 to the cylinders 16 and 40. The valve is positioned initially against the casting 54, as shown in Fig. 2, with the ports 68 open to exhaust. The valve is controlled by an arm 72 which is pivotally mounted at its upper end on a pin 74 supported on a bracket 76 fast on the plate 56. At its lower end the arm carries a pin 78 extending into an annular groove 80 in the valve 58, so that the valve is moved along the tube 60 by the arm. A spring 82 connected to the arm 72 holds the valve in its normal position against the casting 54. Also pivotally mounted on the pin 74 is a lever 84 between one arm of which and a lug 86 on the arm 72 is a compression spring 88. Through this spring the arm 72 is operated to move the valve 58 into position to open communication between the ports 66 and 68 in response to swinging movement of the lever 84 in a clockwise direction with reference to Fig. 2, the movement of the arm being limited by its engagement with a rod 90 threaded in the plate 56. The spring 88 is stronger than the spring 82 and may yield only after engagement of the arm 72 with the rod 90. After being operated by the lever 84 the valve 58 is prevented from returning to its starting position by a latch 92 which is pivotally mounted on the lever and is arranged to engage a shoulder 94 formed on a plate 96 pivotally mounted on a pin 98 on the bracket 76. The plate is adjustable about the pin 98 by a screw 100 bearing on the plate 56 and is held in adjusted position by a screw 102 threaded in the bracket 76.

The lever 84 is operated to move the valve 58 into position to establish communication between the ports 66 and 68 by a segmental member 104 adjustably secured to a rotatable control shaft 106 with which the machine is provided. The member 104 has an inclined face 108 which by engagement with a roll 110 on the lever 84 thus operates the lever and has also an arcuate face 112 concentric with the shaft 106 for engaging the roll thereafter to maintain the valve 58 in the position in which it establishes communication between the chamber 32 and the pipe line 30. When the valve is in this position, determined by engagement of the arm 72 with the rod 90, the latch 92 is positioned over the shoulder 94 by a spring 114 connected to an arm 116 of the latch, but is spaced above the shoulder. When the segmental member 104 passes beyond the roll 110, the spring 82 moves the valve 58 reversely to a position determined by engagement of the latch with the shoulder. When the valve is in this position a portion thereof covers the ports 68, as illustrated by broken lines in Fig. 2, thereby locking the fluid in the pipe line 30 and in the cylinders 16 and 40 to hold the toe rest and the instep support in a substantially positive manner against downward pressure of the shoe thereon. At the proper time thereafter in the cycle of operations of the machine a pin 118 carried by an arm 120 on the control shaft 106 acts on the arm 116 to swing the latch 92 from over the shoulder 94, whereupon the valve 58 is returned to its starting position by the spring 82 to open the ports 68 and thus to cause the toe rest and the instep support to be returned to their starting positions.

The heel rest 10 which further assists in controlling the shoe comprises two blocks 122 mounted on pins 124 the ends of which are rotatable in bearings in the two arms of a U-shaped member 126 which serves as a holder for the blocks. Fas-tened to the blocks by screws 128 is a strip of leather 130 arranged to serve as a cover for the blocks and to engage the end face of the shoe. The holder 126 is mounted to swing about two pins 132 which are fast in the arms 134 of a yoke member 136. The inner ends of the pins 132 are V-shaped and extend between the two blocks 122 to limit turning movements of these blocks about the axes of the pins 124 and also by engagement with the blocks to limit turning movement of the holder 126 about the pins 132. It will be understood that upon engagement of the heel rest with the shoe the holder 126 may turn about the pins 132 and the blocks 122 may turn about their own axes to conform to the contour of the heel-end face of the shoe heightwise of the shoe. The hub of the yoke member 136 is fast on the reduced front end of a rod 138 mounted in a socket formed in a carrier 140 which is fast on a shaft 142 the ends of which are mounted to turn in bearings formed in plates 144 fast on the frame casting 20, only one of these plates being visible in the drawings. The rod 138 may be adjusted lengthwise in the carrier 140 for shoes of different sizes or shapes, and it is held in adjusted position and also held from turning by a pin 146 arranged to enter any one of a plurality of holes 148 in the rod. The pin may be withdrawn from any one of the holes against the resistance of a spring 150 by means of a knob 152 fast on the pin.

Swinging movement of the carrier 140 about the axis of the shaft 142 to apply the heel rest to the shoe is effected by a pair of pistons 154 which are movable in cylinders 156 spaced apart laterally of the shoe and are connected by rods 158 to arms 160 which are parts of the carrier 140 and extend through openings in the frame casting 20, only one of these arms being visible in the drawings. The carrier 140 is thus operated by balanced forces applied in different locations along its axis while providing room for the casting 18 directly under the toe rest and the instep support. One of the cylinders 156 is shown in Fig. 1, and both cylinders are shown diagrammatically in Fig. 5. They are supplied with fluid from the chamber 32 through a pipe line 162. In case there is no shoe in the machine, swinging movement of the carrier 140 in response to movements of the pistons 154 is limited by engagement of a shoulder 164 thereon with the frame casting 20. When fluid is permitted to exhaust from the cylinders 156 the heel rest and its carrier are re-turned to their initial positions by gravity, their movement being limited by engagement of a shoulder 166 on the carrier with the frame casting. Admission of fluid to the cylinders 156 and exhaust of fluid therefrom are controlled by a valve 168 (Fig. 5) which is of the same construction and operates in the same manner as the valve 58 for controlling the movements of the toe rest and the instep support. That is, the valve 168 is moved first to admit fluid to the cylinders 156 by establishing communication between two sets of ports 170 and 172, thereby causing the heel rest to be moved into engagement with the shoe. Thereafter, by a partial reverse movement the valve covers the ports 172, as illustrated by broken lines in Fig. 5, and thereby locks the fluid in the cylinders 156 to render the heel rest substantial-ly positive in its control of the shoe. Later in the

cycle the valve is returned to its initial position against the casting 54 to release the fluid from the cylinders by uncovering the ports 172 and thus to permit the heel rest to return to its initial po-sition. The mechanism for thus operating the valve 168 is not shown in the drawings, since it is essentially of the same construction as the mechanism shown in Fig. 2 for controlling the valve 58.

Having described the invention, what I claim as new and desire to secure by Letters Patent of the United States is:

1. In a machine for operating on shoes, the combination with means for applying pressure to the bottom of a shoe on a last, of a toe rest and an instep support movable heightwise of the shoe into positions to support the shoe against said pressure and relatively movable also heightwise of the shoe to permit them to adjust them-selves to the shoe, and fluid-operated means for moving said toe rest and instep support into their shoe-supporting positions while permitting such relative movement thereof.
2. In a machine for operating on shoes, the combination with means for applying pressure to the bottom of a shoe on a last, of a toe rest and an instep support movable heightwise of the shoe into positions to support the shoe against said pressure and relatively movable also heightwise of the shoe to permit them to adjust themselves to the shoe, fluid-operated mechanism for moving said toe rest and instep support into their shoe-supporting positions while permitting such relative movement thereof, and means for admitting liquid under pressure to said fluid-operated mech-anism to operate it and for thereafter locking the liquid in said mechanism to render the toe rest and instep support substantially positive in their action on the shoe.
3. In a machine for operating on shoes, the combination with means for applying pressure to the bottom of a shoe on a last, of a toe rest and an instep support movable heightwise of the shoe into positions to support the shoe against said pressure and relatively movable also heightwise of the shoe to permit them to adjust themselves to the shoe, and fluid-operated means comprising cylinders and pistons therein for moving the toe rest and the instep support respectively into their shoe-supporting positions, the cylinder and piston associated with the toe rest being of greater diameter than the cylinder and piston associated with the instep support.
4. In a machine for operating on shoes, the combination with means for applying pressure to the bottom of a shoe on a last, of a toe rest and an instep support movable heightwise of the shoe into positions to support the shoe against said pressure and relatively movable also heightwise of the shoe to permit them to adjust themselves to the shoe, fluid-operated means comprising cyl-in-ders and pistons therein for moving the toe rest and the instep support respectively into their shoe-supporting positions by fluid pressure, the cylinders being in communication with each other, and a single valve for admitting operating fluid to both cylinders.
5. In a machine for operating on shoes, the combination with means for applying pressure to the bottom of a shoe on a last, of a toe rest and an instep support for supporting the shoe against said pressure, said toe rest and instep support being relatively movable heightwise of the shoe to permit them to adjust themselves to the shoe, fluid-pressure means for controlling said toe rest

and instep support, and means for admitting liquid under pressure to said fluid-pressure means and for locking the liquid therein to render the toe rest and instep support substantially positive in their action on the shoe.

6. In a shoe machine, the combination with means for operating on a shoe, of a heel rest for engaging the heel-end face of the shoe to support the shoe, said heel rest comprising members arranged to press on the heel-end face of the shoe respectively in different locations heightwise of the shoe and movable relatively to each other about different axes extending laterally of the shoe to permit them to adjust themselves to the shoe, and a support for said members movable lengthwise of the shoe to apply them to the shoe.

7. In a shoe machine, the combination with means for operating on a shoe, of a heel rest for engaging the heel-end face of the shoe to support the shoe, said heel rest comprising members arranged to press on the heel-end face of the shoe respectively in different locations heightwise of the shoe and movable relatively to each other about different axes extending laterally of the shoe to permit them to adjust themselves to the shoe, and a holder supporting said members and itself movable about an axis extending laterally of the shoe further to facilitate the adjustment of said members to the shoe in response to pressure of the shoe thereon.

8. In a shoe machine, the combination with means for operating on a shoe, of a heel rest for engaging the heel-end face of the shoe to support the shoe, said heel rest comprising members

arranged to press on the heel-end face of the shoe respectively in different locations heightwise of the shoe and movable relatively to each other about different axes extending laterally of the shoe to permit them to adjust themselves to the shoe, a holder supporting said members and itself movable about an axis extending laterally of the shoe further to facilitate the adjustment of said members to the shoe in response to pressure of the shoe thereon, and means for limiting such movement of the holder and also the movements of said members about their own axes.

9. In a shoe machine, the combination with means for operating on a shoe, of a heel rest for engaging the heel-end face of the shoe to support the shoe, fluid-operated mechanism for moving said heel rest bodily lengthwise of the shoe into engagement with the shoe, and means for admitting liquid under pressure to said fluid-operated mechanism to operate it and for thereafter locking the liquid in said mechanism to render the heel rest substantially positive in its action on the shoe.

10. In a shoe machine, the combination with means for operating on a shoe, of a heel rest for engaging the heel-end face of the shoe to support the shoe, a support for said heel rest mounted for swinging movement about an axis extending laterally of the shoe to apply the heel rest to the shoe, and a pair of cylinder-and-piston devices spaced apart laterally of the shoe and operative by fluid pressure thus to swing said support.

BERNHARDT JORGENSEN.
